(57) **CLAIM**

The ornamental design for a trash can, as shown and described.

DESCRIPTION

FIG. 1 is a front isometric view of a trash can showing our new design.

FIG. 2 is a rear isometric view thereof.

FIG. 3 is a front view thereof, of which a rear view is identical.

FIG. 4 is a right side view thereof, of which a left side view is identical.

FIG. 5 is a top view thereof; and,

FIG. 6 is a bottom view thereof.

The broken lines in the figures depict unclaimed portions of the trash can only and form no part of the claimed design.

1 Claim, 4 Drawing Sheets

FIG. 1

FIG. 2
